(57) **CLAIM**

The ornamental design for a LED lamp, as shown and described.

DESCRIPTION

FIG. 1 is a front perspective view of a LED lamp according to an embodiment;

FIG. 2 is a front view of the LED lamp of FIG. 1;

FIG. 3 is a rear view of the LED lamp of FIG. 1;

FIG. 4 is a left side view of the LED lamp of FIG. 1;

FIG. 5 is a right side view of the LED lamp of FIG. 1;

FIG. 6 is a top view of the LED lamp of FIG. 1;

FIG. 7 is a bottom view of the LED lamp of FIG. 1;

FIG. 8 is a bottom perspective view of the LED lamp of FIG. 1 shown in use with the light emitting part in diagonal dash-dot lines, light from LEDs inside being reflected downward by the reflector;

FIG. 9 is a front perspective view of a LED lamp according to another embodiment;

FIG. 10 is a front view of the LED lamp of FIG. 9;

FIG. 11 is a rear view of the LED lamp of FIG. 9;

FIG. 12 is a left side view of the LED lamp of FIG. 9;

FIG. 13 is a right side view of the LED lamp of FIG. 9;

FIG. 14 is a top view of the LED lamp of FIG. 9;

FIG. 15 is a bottom view of the LED lamp of FIG. 9;

FIG. 16 is a bottom perspective view of the LED lamp of FIG. 9 shown in use with the light emitting part in diagonal dash-dot lines, light from LEDs inside being reflected downward by the reflector;

FIG. 17 is a front perspective view of a LED lamp according to another embodiment;

FIG. 18 is a front view of the LED lamp of FIG. 17;

FIG. 19 is a rear view of the LED lamp of FIG. 17;

FIG. 20 is a left side view of the LED lamp of FIG. 17;

FIG. 21 is a right side view of the LED lamp of FIG. 17;

FIG. 22 is a top view of the LED lamp of FIG. 17;

FIG. 23 is a bottom view of the LED lamp of FIG. 17; and, FIG. 24 is a bottom perspective view of the LED lamp of FIG. 17 shown in use with the light emitting part in diagonal dash-dot lines, light from LEDs inside being reflected downward by the reflector.

The broken lines shown in the drawings illustrating unclaimed environmental structures form no part of the claimed design. The dash-dot lines shown in FIGS. 8, 16, and 24 to illustrate the light emitting part of the LED lamp form no part of the claimed design.
